UNITED STATES PATENT OFFICE.

MARY ISABEL COOPER, OF HOCKLEY, ENGLAND.

SAFETY TRANSPORT-CARRIER FOR ELECTRIC INCANDESCENT LAMPS.

969,133.

Specification of Letters Patent. Patented Aug. 30, 1910.

Application filed June 11, 1909. Serial No. 501,645.

To all whom it may concern:

Be it known that I, MARY ISABEL COOPER, a subject of the King of Great Britain, residing at Hockley, county of Essex, England, have invented certain new and useful Improvements in Safety Transport-Carriers for Electric Incandescent Lamps; and I do hereby declare the following to be a full, clear, and exact description of the invention, such as will enable others skilled in the art to which it appertains to make and use the same.

This invention relates to a safety carrier for incandescent electric lamps to enable them to be packed in cases for transport with reduced risk of breakage. And further, enables the lamp to be tested and viewed while secured in the carrier and sealed against the removal of the lamp, by which means makers of the lamps are protected against fraud that is now practiced upon them by other broken lamps being returned as broken in transit. A notice is printed upon the carrier seal that no allowance for breakages will be admitted unless the lamp and carrier are returned with the seal unbroken.

To enable the invention to be fully understood, reference should be made to the accompanying drawings.

Figures 1 and 2 illustrate the carrier with lamp in position. Fig. 3 a cross section on line *x y*.

In the construction of the carrier I take a strip of cardboard of suitable width and bend it to have two upright sides *b* with flat bottom *c* and secure between the upright sides *b* by staples *e* a double rack *a* punched with top and bottom holes of a size to hold the lamp by the bulb and socket part. The top ends of the uprights *b* are turned over to form either a double cover *d* as at Fig. 1 or a treble cover as shown at *g* Fig. 2. The covers *d* or *g* have a small hole punched in the middle for the pip of the lamp. *f* a paper

seal secured to a cover and side *b*. By two of the sides of carrier being open enables the lamp to be viewed and tested while in carrier and so prevent fraudulent substitution of returned breakages.

Having now described my invention, what I desire to secure by Letters Patent of the United States is—

1. An incandescent lamp bulb carrier, comprising a housing having an imperforate bottom, a pair of imperforate side walls and an imperforate hinging top, means for supporting the lamp bulb, and means for sealing said top, said housing being open on at least one side, whereby the whole of the lamp bulb may be examined and electrical connections made to test the lamp before opening the package, substantially as described.

2. An incandescent lamp bulb carrier, comprising a housing formed from a strip of stiff flexible material bent upwardly to leave a central portion or bottom and thence foldable downwardly to form a top closure, said strip of material being of sufficient width to form a shield for said lamp bulb, and said housing being open on two sides, spaced internal cross members carried by the upright walls of said housing and provided with apertures of different diameters to snugly receive and support the bulb portion and the neck portion of the lamp, and means for sealing said foldable top, the whole being so constructed that the entire lamp body may be examined and electrical connections made to test the lamp before opening the package, substantially as described.

In testimony whereof, I affix my signature, in presence of two witnesses.

MARY ISABEL COOPER.
